Primary Examiner — S. Bryan Reinholdt, Jr.(74) *Attorney, Agent, or Firm* — Boyle Fredrickson, S.C.; Kirk L. Deheck(57) **CLAIM**

The ornamental design for a firearm top cover mount, as shown and described.

DESCRIPTION

FIG. 1 is a perspective view of a firearm top cover mount incorporating my new design viewed from in front of, above, and a left side thereof;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.

The uniformly broken lines shown in the figures represent portions of the firearm top cover mount that form no part of the claimed design. The dot-dashed broken lines shown immediately adjacent the shaded areas represent boundaries to the claimed design and forms no part of the claimed design.
